M. MIRKIN

BATHTUB

Filed Nov. 28, 1925

UNITED STATES PATENT OFFICE.

MAX MIRKIN, OF NEW YORK, N. Y.

BATHTUB.

Application filed November 28, 1925. Serial No. 72,005.

This invention relates to improvements in bath tubs, and more particularly to small, portable, self-contained bath tubs, provided with attachments rendering the same especially adaptable for the bathing of children.

In order that a clearer perception of the present invention may be had, it is to be noted that infants' bath tubs are of a size and shape as to render them inconvenient in use when it is desired to have what might be termed a shallow bath or a deep bath, and the present invention is directed more particularly to such bath tubs provided with supporting means covering the bottom which may be raised and lowered either at one end or both ends to form an inclined or horizontal bath, as desired.

With this idea in mind, one of the objects of the present invention is to provide a small and practical bath tub with an adjustable attachment combined therewith, which may be inexpensively manufactured and assembled.

A further object is to provide a device of the above general character which may be easily and quickly taken apart, and thoroughly cleaned, thus rendering the device perfectly sanitary.

A further object of the invention is to provide a device of the first above mentioned character, in which the interior walls of the tubs will be free from projections or any projecting parts, which might tend to injure or scratch the infant.

Other objects will be in part obvious or hereinafter pointed out in the following analysis of this invention when taken in connection with the accompanying sheet of drawings, illustrating one of various possible embodiments thereof. In these drawings, wherein similar parts are indicated by corresponding reference characters,—

Figure 1 is an elevation view, partly in section, showing the complete device in operative position;

Figure 2 is a plan view of the parts shown in Figure 1;

Figure 3 is a detail perspective view of one of the parts, and

Figure 4 is a similar view showing a slight modification.

While the present invention will be hereinafter described with particular relation to infants' bath tubs, it is, of course, to be understood that without material modifica-

tion, various features herein shown and described may be incorporated in other tubs.

Referring now to the drawing in detail and more particularly to Figures 1 and 2, 60 10 indicates a bath tub which may be of any desired shape, altho it is preferred to construct the tubs in the outline shown in Figure 2; that is, generally elliptical in form, but slightly wider at one end than at the other. The circular ends of the tubs are provided with vertically disposed grooves 11 being substantially rectangular in horizontal cross-section, and of a depth substantially equal to the depth of the tub. The 70 extreme outer wall of this groove 11 is provided with one or more headed rivets 12 adapted to co-act with key-hole openings 13 in an adjusting device 14 shown in Figure 3. This adjusting device comprises an elongated strip of material bent back upon itself and provides a finger opening 15, which may be grasped to raise and lower the adjusting means, as desired. The lower part of this member is provided with a part 16 bent at 80 right angles to the main body portion and terminating in a curved eyelet 17 through which the curved rod 18, shown in Figure 2, is adapted to pass. This rod 18 has a telescopic engagement with a tubular member 20, whereby a certain amount of adjustability is permitted by sliding the two curved members 13 in and out of this rod. The two rods 20, one at each side, and the two curved members 18, one at each end, 90 provide a frame adapted to co-act with a cradle support 21. This cradle support is preferably made of heavy canvas or the like, and is provided at each side with an open hem through which the tubes 20 pass prior 95 to their reception of the end members 18. Each end of this cradle 21 is provided with a flap 22 provided with a hole 23, whereby it may embrace the cross member 18 at each side of the adjusting device 15 before being 100 buttoned or otherwise secured by the fastening devices 24.

In Figure 4, there is shown a slight modification; that is, the tub 10 having recessed portions 11 has the adjusting rivets 12 projecting on the outside and the adjusting device 25 with key-hole openings 26 engage the outer surface of the tub while the inner surface 25 of the adjusting member just fits and closes the entrance to this longitudinal channel. In this manner, the channel is completely closed and the part 25 provides a

flush even surface about the interior of the tub. Also, it is to be noted that this member 25 is provided with an eyelet 17 for engaging the curved member 18, as above described. The tub is preferably provided with a faucet 27 to permit drawing or filling through rubber tube 28.

It is believed that the operation and method of use of this device will be perfectly clear from the above description. It may be stated, however, that in use, the parts are assembled substantially as shown in Figure 1 and the tub filled to the desired degree with water, as through tube 28 connected with the spigot in a wash bowl, for example. During or after the bath, as desired, the cradle 21 may be moved up and down to any desired depth and securely held in adjustable position. Either one end or both ends may be moved, and should one end be moved alone, there would be a consequent elongation of the cradle, which would be taken up by the adjustability of the parts 18 within the tubes 20, together with the natural stretch of the wet fabric forming the cradle. In this way, the entire bottom of the tub is covered at all times. By reason of the recessed adjusting means at each end of the tub, there are no projections or corners exposed, thereby preventing injury to the infant. Furthermore, owing to the simplicity of design and the ease with which the device may be taken apart to be cleaned, its sanitary features will be apparent.

It is thus seen that the present invention contemplates a practical device well adapted to accomplish, among others, all of the objects and advantages herein set forth.

40 I claim:

1. In combination with a tub having oppositely disposed recessed portions, supporting device associated with said recessed portions, adjusting devices cooperating therewith, and adapted to close the open side of the recessed portions, and a cradle suspended between said adjusting devices.

2. In combination with a tub having oppositely disposed recessed portions, supporting device associated with said recessed portions, adjusting device cooperating therewith, and adapted to close the open side of the recessed portion, and a cradle suspended between said adjusting devices, said cradle comprising a telescopic frame work construction whereby elongation of the cradle may be obtained, when desired.

3. In combination with a tub having op-

positely disposed recessed portions, supporting devices associated with said recessed portions, U-shaped adjusting devices having openings on one side cooperating with said supporting devices, the opposite side of said adjusting device being adapted to close the open side of the recessed portion of the tub, and a cradle suspended from said adjusting device.

4. In combination with a tub having oppositely disposed recessed portions, supporting devices associated with said recessed portions, U-shaped adjusting devices having openings on one side cooperating with said supporting devices, the opposite side of said adjusting device being adapted to close the open side of the recessed portion of the tub, and a cradle suspended from said adjusting device, said cradle comprising a closed frame work.

5. In combination with a tub having oppositely disposed recessed portions, vertical adjusting devices mounted in said recessed portions, having a portion thereof adapted to close the open side of the recessed portion, and a cradle supported from said adjusting devices comprising a telescopic frame work and a canvas bottom suspended from said frame work, whereby a certain amount of elongation may take place should one of said adjusting devices be raised independently of the other.

6. In combination with a tub having oppositely disposed recessed portions, vertical adjusting devices mounted in said recessed portions each having a portion thereof adapted to close the open side of one recessed portion, and a cradle supported from said adjusting devices comprising a telescopic frame work and a canvas bottom suspended from said frame work, whereby a certain amount of elongation may take place should one of said adjusting devices be raised independently of the other, said parts being freely detachable one from the other, whereby they may be easily and quickly disassembled for cleaning purposes.

7. A cradle adapted to be used with a bath tub comprising a telescopic frame suspended coextensive with the bottom of the tub with which it is used and a canvas bottom suspended from said framework together with means for adjusting said cradle at one or both ends relative to the bottom of the tub, as desired.

Signed at New York, New York, this 20th day of November, 1925.

MAX MIRKIN.
